CLAIM

The ornamental design for a Christmas tree collar as shown and described.

DESCRIPTION

FIG. 1 is a rear, right and bottom perspective view of a Christmas tree collar, showing my new design.

FIG. 2 is a rear, left and top perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged perspective view of an encircled portion labeled, "9," in FIG. 1; and,

FIG. 10 is an enlarged perspective view of an encircled portion labeled, "10," in FIG. 1.

The dashed broken lines depict portions of the Christmas tree collar that form no part of the claimed design.

The dot-dash broken lines in FIGS. 1, 9 and 10 depict the boundaries of the enlargements and form no part of the claimed design.

1 Claim, 10 Drawing Sheets
